UNITED STATES PATENT OFFICE.

MICHAEL W. MAYER, OF ALLEGHENY, PENNSYLVANIA.

RAIL-JOINT.

SPECIFICATION forming part of Letters Patent No. 695,221, dated March 11, 1902.

Application filed December 18, 1901. Serial No. 86,364. (No model.)

To all whom it may concern:

Be it known that I, MICHAEL W. MAYER, a citizen of the United States of America, residing at Allegheny, in the county of Allegheny and State of Pennsylvania, have invented certain new and useful Improvements in Rail-Joints, of which the following is a specification, reference being had therein to the accompanying drawings.

10 This invention relates to certain new and useful improvements in rail-joints, and relates more particularly to that class wherein the use of nuts and bolts is entirely dispensed with.

15 The present invention has for its object the provision of novel means whereby the two rail-sections may be easily and conveniently placed together and firmly secured; furthermore, to provide novel means that will allow 20 for the usual expansion and contraction of the rails.

25 Another object of the present invention is to provide a rail-joint that will be extremely simple in construction, strong, durable, and comparatively inexpensive to manufacture.

With the above and other objects in view the invention consists in the novel combination and arrangement of parts to be herein-after more fully described, and specifically 30 pointed out in the claims.

35 In describing the invention in detail reference is had to the accompanying drawings, forming a part of this specification, and wherein like numerals of reference indicate like parts throughout the several views, in which—

Figure 1 is a perspective view of my improved rail-joint, showing the same secured in position to the rails. Fig. 2 is a vertical 40 sectional view of the rail, showing an end elevation of the rail-joint. Fig. 3 is an under plan view of the same. Fig. 4 is a perspective view of one of the tie-plates. Fig. 5 is a similar view of one of the yokes. Fig. 6 is a perspective view of the rod securing the yokes. Fig. 7 is an under plan view of the tie-plate as illustrated in Fig. 4. Fig. 8 is a plan view of the cushioning-plate secured under the rails and connecting the tie-plates.

50 In these drawings the reference-numeral 1 indicates the rails, and 2 indicates the cross-tie.

The numeral 3 represents one of the tie-plates having downwardly-extending flanges 4, said tie-plates having openings 5 formed 55 therein to receive spikes or other fastening means, which serve to connect the tie-plates to the tie, said tie-plate 3 also having formed therein a cut-away portion 6 on each side. These tie-plates carry integral fish-plates 7, 60 the under face of the tie-plates carrying projections 8, the latter engaging in corresponding openings 9, formed in the cushioning-plate 10, the latter serving to connect the tie-plates together.

65 The reference-numeral 11 indicates the yoke, in which are formed openings 12 12, said yoke extending into the recess 6 and serving to secure the rail-joint and integral fish-plates together. These yokes are connected together 70 by means of rods 14, carrying on their one end a head 15 and having formed at their other extension split ends 16. These rods 14 pass through the openings 12 and are held in position by means of the heads 15 and split ends 75 16, as shown in Fig. 1 of the drawings.

70 The manner of connecting the rails together endwise, as well as the many advantages obtained by such operation, will be readily apparent from the foregoing description taken 80 in connection with the accompanying drawings.

It will be noted that various changes may be made in the details of construction without departing from the general spirit of my invention.

85 Having fully described my invention, what I claim as new, and desire to secure by Letters Patent, is—

1. In a rail-joint, the combination with the 90 ties, a tie-plate secured thereon, integral fish-plates carried by said tie-plates, the rails being secured in said fish-plates, removable yokes arranged at each side of said tie-plate, and means passing through the ends of each 95 of said yokes and engaging the upper face of the tie-plate, to fasten said plates together, substantially as described.

2. In a rail-joint, the combination with the 100 ties, a tie-plate secured thereon, integral fish-plates carried by said tie-plates, the rails being secured in said fish-plates, removable yokes arranged at each side of said tie-plate, and rods carrying heads and split ends to fas-

ten said plates together, substantially as described.

3. In a rail-joint, the combination with the tie, a tie-plate secured thereon, integral fish-
5 plates carried by said tie-plates, a cushioning-
plate securing said tie-plates together, the
rails being secured in said fish-plates, remov-
able yokes arranged at each side of said tie-

plate, and means to fasten said plates together,
substantially as described.

In testimony whereof I affix my signature
in the presence of two witnesses.

MICHAEL W. MAYER.
